COIN HOLDERS

Milton Levy, 664 Zola St., Woodmere, N.Y.
Filed Mar. 22, 1962, Ser. No. 181,574
1 Claim. (Cl. 206—82)

This invention relates to new and useful improvements in coin holders such as disclosed in my Letters Patent 2,985,284.

A primary object of the invention is to provide a coin holder having a body composed of two complementary halves adapted to be interlocked by swinging relative to each other.

Another object of the invention is to provide a coin holder having a body composed of two complementary halves providing a space for an envelope containing a coin and having a window for exposing the coin.

A further object is to provide a coin holder having a body of opaque rigid plastic material composed of two complementary halves providing a space for an envelope containing a coin and having a window for exposing the coin, the outer surface of the body being suitable for writing thereupon.

Still another object of the invention is to provide a coin holder having a body composed of two complementary halves providing a space for an envelope containing a coin and having a window for exposing the coin, the halves having means for properly positioning the halves.

Yet another object of the invention is to provide a coin holder having a body composed of two complementary halves providing a space for an envelope containing a coin, the halves having means for guiding the envelope to proper position between the halves.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

FIG. 1 is a top plan view of a coin holder embodying my invention, a coin being shown in supported position.

FIG. 2 is a sectional view taken on the line 2—2 of FIG. 1, on an enlarged scale, parts being broken away.

FIG. 3 is an enlarged cross-sectional view taken on line 3—3 of FIG. 1, parts being broken away.

FIG. 4 is an enlarged sectional view taken on the line 4—4 of FIG. 1.

FIG. 5 is an enlarged sectional view taken on the line 5—5 of FIG. 1.

FIG. 6 is a disassembled perspective view of the holder.

FIG. 7 is an enlarged fragmentary sectional view of one of the hinge parts.

FIG. 8 is a similar view of another hinge part.

FIG. 9 is an enlarged sectional view taken on the line 9—9 of FIG. 6.

Referring in detail to the various views of the drawing, in FIG. 1 a coin holder embodying the invention is shown and indicated generally by the reference numeral 10. The coin holder is preferably formed of opaque plastic material, such as styrene, but may of course be made of metal or other suitable material.

The coin holder comprises a pair of complementary plates 12 and 14 substantially square in configuration and of similar dimensions with a circular opening constituting a window 16 centrally of each plate. The plates are hingedly connected together at one end thereof. This connection includes inwardly extending lugs 18 and 20, along the side 22 of plate 12 at the corners thereof. Lug 18 on its inner face is formed with a semispherical projection 24, and lug 20 on its inner face is formed with a

2

similar shaped socket 26. Plate 14 is formed with an elongated inwardly extending flange 28 on the side 30 of the plate adapted to fit in the space between the lugs 18, 20. On its face adjacent lug 18, flange 28 is formed with a semispherical socket 30 adapted to coact and receive the semispherical projection 24 on lug 18, and on its opposite face adjacent lug 20, the flange is formed with a semispherical projection 32 adapted to coact with and to be received in the socket 26 in the face of lug 20. The projections 24, 32 and sockets 26, 30 constitute the hinges of the holder.

Plate 12 along its side opposite the hinges is formed with a pair of outwardly extending flanges 34, 34 adjacent its corners leaving a clearance 36 therebetween along the side. The material of the sides is cut away centrally thereof forming a slanting notch 38, slanting downwardly and outwardly as viewed in FIG. 6. Along its sides 40, 40, plate 12 is also provided with opposed inwardly extending flanges 42, 42, each flange being formed with an elongated inwardly extending ridge 44 on its inner surface.

Plate 14 is formed along its side 46 with an inwardly extending flange 48. A lug 50 is formed on the inner surface of flange 48 shaped to fit and snap into and over the notch 38 in plate 12 to detachably hold the plates together. The plate 14 is also formed along its sides 52 with pairs of inwardly extending flanges 54, 54 adjacent the outer corners thereof and a similar pair of inwardly extending flanges 56, 56 adjacent the inner corners thereof, leaving clearances 58, 58 between the pairs of flanges. Sides 52 of plate 14 are also formed centrally thereof with cut away portions forming slanting notches 60, 60.

When the plates are in closed position as shown in FIG. 1, the flange 48 is received in the clearance 36 between flanges 34, 34 on the plate 12, and the flanges 42 on the sides 40 of plate 12 are received in the clearances 58 between the corner flanges on sides 52 of plate 14, with ridges 44 interlocking with notches 60, 60, whereby the plates are nested and interlocked to each other, leaving a space or clearance 62 therebetween as seen in FIG. 2.

A substantially square envelope or packet 66 of thin transparent flexible plastic film material is adapted to be positioned and clamped in the space 62 between the complementary plates 12 and 14. On three of its sides, the envelope is sealed by means of adhesive or the like, leaving one side unfastened to serve as a mouth for insertion of a coin 68. The dimensions of the envelope are commensurate with the dimensions of the plates so that when inserted, the flanges 42, 54 and 56 serve to center the envelope in the space 62 so that the coin 68 will be in register with the windows 16, 16 so as to expose the coin on both sides thereof.

The plates 12 and 14 may be readily opened or separated by manually pressing or twisting one plate away from the other, the outer side edges of both plates 12 and 14 adjacent the corners being formed with fingernail depressions 70 and 72, respectively, for this purpose.

The invention comprehends that the holder may be used as a permanent mount for 35 mm. photo transparencies and for this purpose the windows may be rectangular in shape instead of being circular.

While I have illustrated and described the preferred embodiment of my invention, it is to be understood that I do not limit myself to the precise construction herein disclosed and that various changes and modifications may be made within the scope of the invention as defined in the appended claim.

Having thus described my invention, what I claim as new, and desire to secure by United States Letters Patent is:

A coin holder comprising a pair of complementary sub-

stantially square-shaped plastic plates hingedly connected to each other, said plates having aligned central circular windows, said plates when closed providing a space therebetween, a transparent envelope in said space, the transparent envelope containing a coin for exhibition through the windows, coating ridges and notches on the plates for interlocking with each other to hold the plates juxtaposed, and inwardly extending opposed flanges on the side edges of the plates, mounting said ridges, for centering the envelope between the plates whereby the coin contained in the envelope is exposed through the windows, said plates having fingernail depressions on the outer surfaces thereof on the sides thereof opposite the hinged sides, said depressions facilitating separation of the plates, said hinge connection including ball and socket joints between the plates on one side thereof adjacent the perpendicularly disposed sides thereof.
